(57) CLAIM

The ornamental design for a puppet, as shown and described.

DESCRIPTION

FIG. 1 is a front view of a puppet showing my design
FIG. 2 is a right side view thereof;
FIG. 3 is a front view of an alternate position thereof;
FIG. 4 is a right side view of FIG. 3;
FIG. 5 is a front view of a second alternate position thereof;
FIG. 6 is a right side view of FIG. 5;
FIG. 7 is a front view of a third alternate position thereof;
FIG. 8 is a right side view of FIG. 7;
FIG. 9 is a left side view of FIG. 7;
FIG. 10 is a rear view thereof;
FIG. 11 is a top view thereof; and,
FIG. 12 is a bottom view thereof.

The broken lines shown in FIG. 10 are for the purpose of illustrating portions of the puppet and form no part of the claimed design.
